(57) **CLAIM**

The ornamental design for a holder for storage boxes, as shown and described.

DESCRIPTION

FIG. 1 is a front, top and left side perspective view of a holder for storage boxes in accordance with the new design;

FIG. 2 is a rear, bottom and left side perspective view thereof;

FIG. 3 is a front elevation view thereof;

FIG. 4 is a left side elevation view thereof;

FIG. 5 is a right side elevation view thereof;

FIG. 6 is a top plan view thereof; and,

FIG. 7 is a top plan view thereof.

The broken lines are for the purpose of illustrating the environment of the design only and form no part of the claimed design.

It is certified that error appears in the above-identified patent and that said Letters Patent is hereby corrected as shown below:

Delete the title page and substitute the attached title page therefor.

On the Title page of the patent, Item (73) Assignee, replace Raaco International A/S (DK) with
--raaco International A/S (DK)--.

On the Title page of the patent, in the Description section, after FIG. 5 is a right side elevation view thereof; add --and--.

On the Title page of the patent, in the Description section, replace FIG. 6 is a top plan view thereof; and FIG. 7 is a top plan view thereof. with --FIG. 6 is a top plan view thereof--.

Delete all drawing sheets and substitute the attached drawing sheets (1-6) therefor.

In the Drawings, delete FIG. 7.

Signed and Sealed this
Twenty-third Day of July, 2013

Teresa Stanek Rea
Acting Director of the United States Patent and Trademark Office
